UNITED STATES PATENT OFFICE.

ERNST EVALD OTTERSTRÖM, OF STOCKHOLM, SWEDEN.

BRICK WALL.

1,395,764.

Specification of Letters Patent. Patented Nov. 1, 1921.

Application filed February 28, 1920. Serial No. 361,952.

To all whom it may concern:

Be it known that I, ERNST EVALD OTTERSTRÖM, a subject of the King of Sweden, residing at Stockholm, Sweden, have invented 5 new and useful Improvements in Brick Walls, of which the following is a specification.

The present invention relates to a brick wall consisting essentially of bricks in two 10 different groups, of which the one group—the first group—in section shows two recumbent bricks and between them erect bricks, and the other group, which is of the same height as the first group, consists of 15 erect bricks. This brick wall can be performed in such a way that its respective main layers in section of the wall show one of each of the two groups of bricks, with the groups placed alternately on different sides 20 of the wall in layers lying over one another. Further, bricks standing edgewise can be arranged between one or both kinds of brick-groups.

By constructing a brick wall in accordance with the present invention, the advantage is attained that, owing to the fact that most of the bricks are placed erect, a greater strength of brickwork per net area is obtained than in an ordinary wall with recum- 25 bent bricks, as has been shown by experiments. In explanation of this fact it may be observed that the walls in question have, per height meter of wall, a far smaller number of joints than an ordinary wall, and it is a 30 well-known fact that a large quantity of mortar has a very injurious effect on the strength of the brickwork. Moreover, by this construction it is possible in a simple and practical manner to produce a brick wall 35 with lengthy reinforcements of wood, ferro-concrete, or the like within it, which wall in the case of heavy loads has many advantages over a wall of bricks solely. The present wall also combines with the desirable slender- 40 ness and lightness, great insulating capacity and protection against moisture owing to the non-existence of through joints, whether vertical or horizontal. In addition to the above, there are attained the advantages of great saving of bricks and mortar, 45 simple foundation, and economy of space. The method of bricklaying, for the rest, does not afford any greater difficulties than in ordinary bricklaying.

On the accompanying drawing is shown, merely by way of example, a brick wall per-

formed in accordance with the present invention with reinforcing beams of wood. Figure 1 shows the wall in elevation, Fig. 2 in vertical section along the line 2—2 in Fig. 60 1, Fig. 3 in horizontal section along the line 3—3 in Fig. 1, and Fig. 4 in horizontal section along the line 4—4 in Fig. 1.

The wall shown consists of two walls 1 and 2 running side by side. Each of these 65 walls has two kinds of alternating layers, of which the one kind 3 has a brick 4 placed edgewise (on short-edge) in the longitudinal direction of the wall, alternately, looking in the longitudinal direction of the wall, with 70 two bricks 5, 6 placed (on long-edge) on top of one another lengthwise in the longitudinal direction of the wall, whereas the other kind 7 has two bricks 8, 9 placed side by side edgewise (on short-edge) in the transverse 75 direction of the wall, alternately, looking in the longitudinal direction of the wall, with a group of four bricks 10, 11, 12, 13 arranged in the longitudinal direction of the wall, of which two 10, 11 are placed edgewise 80 (on long-edge) side by side (if necessary, with some space 14), looking in the transverse direction of the wall, between two recumbent bricks 12, 13, besides which the single brick 4 in the one layer 3 is straight 85 above or under, respectively, the four-group 10, 11, 12, 13 in the other layer 7. As is evident from Fig. 2, the wall shows in section two groups of bricks, the one (the first group) 10, 11, 12, 13, and the other the 90 group 5, 6, which are placed alternately on different sides of the wall in layers lying above one another. These two groups of bricks form between them channels 15. In the example shown there occur also, horizontally and vertically passing, reinforcing beams 16 or 17 of wood, which are united with one another into a framework. For the horizontal reinforcing beams 16 there are lengthwise channels, which have been ob- 95 tained simply by omitting the bricks 11 and by replacing the bricks 8, 9 with a single brick 18 placed edgewise (on short-edge), looking in the longitudinal direction of the wall; and, at the same time, by replacing the 100 bricks 8, 9, as stated, with the brick 18, vertical channels have been obtained for the 105 vertical reinforcing beams 17.

The detailed parts in the wall shown may of course be varied in many ways, provided 110 only that the characteristic feature of the invention is retained. In a complete condi-

tion the wall shown should be finished on both sides.

What I claim is:

1. A brick wall, consisting essentially of 5 bricks in two different groups, one group of which in section shows two recumbent bricks and between them erect bricks, and the other group of the same height as the first group and consisting of erect bricks.
- 10 2. A brick wall, consisting essentially of bricks in two different groups, one group of which in section shows two recumbent bricks and between them erect bricks, and the other group of the same height as the 15 first group and consisting of erect bricks, the respective main layers of the wall in section showing the groups placed in alternate layers on different sides of the wall, with one of each of the two groups lying 20 over one another.
- 15 3. A brick wall as stated in claim 1, characterized by the fact that between the kinds of brick-groups there are placed bricks standing edgewise.
- 25 4. A brick wall as stated in claim 1, characterized by the fact that in the layers

at different heights of the wall are arranged lengthwise channels, in which elongated reinforcing members are placed.

5. A brick wall as stated in claim 1, 30 characterized by the fact that vertical channels are arranged at a suitable distance from one another, looking in the longitudinal direction of the wall, in which channels elongated reinforcing members are placed. 35

6. A brick wall as stated in claim 4, characterized by the fact that the lengthwise channels are formed by the omission of the inner erect brick in the first group and by placing the bricks standing edgewise between the first brick-groups in such wise 40 that they do not present any obstruction in the said channels.

7. A brick wall as stated in claim 5, characterized by the fact that at the places 45 where the vertical channels are to be formed, the bricks which stand edgewise between the first groups of bricks are placed in the longitudinal direction of the wall.

In testimony whereof I have signed my 50 name to this specification.

ERNST EVALD OTTERSTRÖM.
